GALE HOOD

Hyman H. Mishel, Philadelphia, Pa.

Application February 2, 1944, Serial No. 520,778

1 Claim. (Cl. 2-84)

1

This invention relates to a combined hood and cape for protection against wind and rain.

An object of this invention is to provide a lady's garment in the form of a combined hood and cape which is of such construction that it will readily fold up into a small package for carrying in a purse.

Another object of this invention is to provide a garment or article of wearing apparel of this kind which can be made of light, waterproof fabric, or may be made of heavier fabric adapted to keep the wearer warm and protect the wearer against winds, rain and cold.

The combined hood and cape embodies a substantially circular cape which is split at the front and may be tied, buttoned or otherwise fastened together, and a hood which is designed to engage over the head in a manner loose enough so that the hood may cover a small hat, the hood being provided with a visor which may be swung from a position overlapping the hood to a forwardly projecting position.

With the foregoing objects in view, and others which may hereinafter more fully appear, the invention consists of the novel construction, combination and arrangement of parts as will be more specifically described, and illustrated in the accompanying drawings wherein is shown an embodiment of the invention, but it is to be understood that changes, variations and modifications may be resorted to which fall within the scope of the invention, as claimed.

In the drawings:

Figure 1 is a detail side elevation of a preferred form of hood and cape;

Figure 2 is a fragmentary front elevation of the invention;

Figure 3 is a fragmentary sectional view taken on the line 3-3 of Figure 1;

Figure 4 is a fragmentary sectional view taken on the line 4-4 of Figure 1;

Figure 5 is a fragmentary sectional view taken on the line 5-5 of Figure 1; and

Figure 6 is a fragmentary sectional view taken on the line 6-6 of Figure 1.

Referring now to Figures 1 to 6 inclusive there is disclosed a combined hood and cape, which is adapted to be made out of waterproof material. The hood 15a is formed of members 17a and 18a secured together by stitching and the hood forming members 17a and 18a, at their forward edges, as indicated at 50 and 51, cross each other. The hood 15a has secured to the forward edge thereof, a visor 24a. The visor 24a, however, is formed of two plies of material 52 and 53 which, at their

2

inner edges, are provided with a double fold, as indicated at 54 and 55 respectively and the hood 15a, at its forward edge, is also reverted, as indicated at 56. The reverted portions of the hood 5 and visor are then stitched together by stitching 57. The outer or forward edges of the visor forming members 52 and 53 are folded reversely, as indicated at 58 and 59, the fold 58 being a double fold and the folded portions 58 and 59 are then stitched, as by stitching 60, to the visor forming members 52 and 53.

The cape 16a, in the present instance, is formed of a substantially semi-circular piece of fabric, which is preferably made from two fabric pieces 15 61 and 62 stitched together along the line 63. Along the line 63 connecting the cape members 61 and 62, there are secured a pair of tapes 64 which provide one means for securing the open front portions of the cape together. As shown in 20 Figure 3, the cape member 61 has the free edge formed into a double fold, as indicated at 65, and the adjacent edge of the cape member 62 is also formed into a single fold 66. The tape 64 is formed into a single fold, as indicated at 67, and 25 the folded portions of the cape members 61 and 62 are stitched together and the tape 64 stitched to the folded portions of the cape sections by stitching 68. The lower marginal portion of the cape 16a is folded into a reverse fold or hem, as 30 indicated at 69, which is secured to the body of the cape 16a by stitching 70. The free edge of the cape section 61, which is adapted to overlap the cape section 62, is formed, as shown in Figure 6, with a double fold 71, and one end of each 35 of a pair of tapes 72 is formed into a single fold 73 for interlocking with the double bend or fold 71 and stitching 74 secures the folded portion 71 and the ends of the tapes 72 to the free edge of the cape section 61.

40 The combined hood and cape hereinbefore described is adapted to be made out of fabric, preferably waterproof fabric, which is of such construction that when the device is not worn it may be readily folded into a relatively small package. 45 The hood 15a forms a protecting element for the hair of the wearer in addition to the head so that the head of the wearer will not become wet in rainy weather and in addition the hair of the wearer will not be blown by the wind. The visor 50 24 may be worn in either forwardly projecting relation so as to protect the face of the wearer, or it may be folded rearwardly, as shown in Figure 1, where the visor overlaps the forward upper portion of the hood. The cape is firmly secured 55 by the tapes 64 and 72.

The cape is fastened by overlapping the separated forward portions thereof as shown in Figure 2, and then tying the complementary tapes 64 and 72. That portion of the hood below the visor constitutes a protecting medium for the neck of the wearer and, as shown in Figure 2, the neck covering portions of the hood at the front overlap or cross each other at a point below the chin of the wearer.

This combined hood and cape may be made in any desired color and will form an attractive garment for protecting the wearer against wind or rain, or both. The cape is preferably of sufficient size to engage completely over the shoulders of the wearer and projects slightly beyond the shoulders.

I claim:

A combined hood and cape comprising a substantially circular cape member open at the front thereof, a hood secured to and extending upwardly from said cape member, said hood comprising a pair of opposed flexible hood forming members having substantially straight forward

edges, convex upper edges, and substantially straight rear edges merging into said convex upper edges, means securing said upper and rear edges together, said cape comprising a pair of sector-shaped sections, means securing one edge of one section to an adjacent edge of the other section, a pair of tapes carried by the free edge of one section, and a second pair of tapes fixed between the secured edges of said sections.

HYMAN H. MISHEL.
